UNITED STATES PATENT OFFICE.

HARRY W. JOHNSON, OF LIMA, OHIO.

SWIMMING-MITT.

SPECIFICATION forming part of Letters Patent No. 742,440, dated October 27, 1903.

Application filed February 10, 1903. Serial No. 142,700. (No model.)

To all whom it may concern:

Be it known that I, HARRY W. JOHNSON, a citizen of the United States, residing at Lima, in the county of Allen and State of Ohio, have invented certain new and useful Improvements in Swimming-Mitts, of which the following is a specification.

This invention has relation to swimming appliances chiefly designed for the hand, being a mitt of light material—such as rubber, oil-silk, or waterproof textile—and of ample size to form webs between the fingers of the hand when stretched or spread to their utmost capacity.

15 The mitt is approximately of pear form and is provided at the small end with a wristband of rubber to form a tight joint about the wrist, so as to exclude air and water, this being essential to the proper formation of the webs 20 between the fingers of the hand when the mitt is in position thereon.

The invention will be described more in detail hereinafter and is shown in the accompanying drawings, in which—

25 Figure 1 is a detail view of a hand with the mitten thereon, the fingers being spread or extended. Fig. 2 is a section about on the line X X of Fig. 1. Fig. 3 is a detail view of the mitt.

30 Corresponding and like parts are referred to in the following description and indicated in all the views of the drawings by the same reference characters.

The mitt 1 is preferably constructed of thin 35 rubber, although oil-silk or waterproof textile may be the material from which it is formed, and it is of pear shape and of such dimensions as to provide webs between the fingers of the hand when worn thereon and 40 the air is exhausted. An elastic band 2 is provided at the small end of the mitt to close the same tight about the wrist without injurious pressure thereon. It is preferred to construct the mitt of light rubber, which gives 45 to the webs a certain amount of elasticity, thereby materially assisting the swimmer.

The mitt is slipped upon the hand, after which the fingers are spread or separated and the air exhausted from the mitt. This causes 50 the opposite parts of the mitt between the fingers to come close together and the parts op-

posite the fingers to be pressed close thereabout, producing the plexus effect shown in Fig. 1. The air is exhausted from the mitt by doubling up the hand and pressing the 55 parts of the mitt close together or in any convenient way. To remove the mitt, it must be stripped from the hand. A pair of mitts may be inflated and joined by a cord and may be used to buoy up a person by passing the cord 60 or connection beneath the arms.

While the device is designed most especially for the hand, it is obvious that it may be used as a buoy to sustain the person. In this application the mitt is inflated, the wrist 65 end being secured by means of a cord to confine the air, and is attached to the body to be buoyed in the most advantageous and convenient way.

Having thus described the invention, what 70 is claimed as new is—

1. A swimming appliance to be fitted to the hand so as to embrace the fingers and form webs therebetween, the same consisting of a mitt of light pliable material impervious to 75 moisture and adapted to have its opposite side portions pressed together by atmospheric pressure, substantially as specified.

2. A swimming appliance to be fitted to the hand so as to embrace the thumb and fingers 80 and form webs therebetween, the same consisting of a mitt of approximately pear-shaped having an elastic band at the small end to close the mitt about the wrist, said mitt being formed of impervious material and adapted 85 to have its opposite sides pressed together by atmospheric pressure, substantially as specified.

3. An article of manufacture, a swimming-mitt of light rubber of approximately pear-shaped, and having its small end reinforced 90 and adapted to close tight about the wrist, the mitt being adapted to fit close about the fingers and to form webs therebetween due to atmospheric pressure on opposite sides there- 95 of, substantially as described.

In testimony whereof I affix my signature in presence of two witnesses.

HARRY W. JOHNSON. [L. S.]
